UNITED STATES PATENT OFFICE.

ROBERT W. SCOTT, OF BABYLON, NEW YORK, ASSIGNOR TO SCOTT AND WILLIAMS, INC., OF NEW YORK, N. Y., A CORPORATION OF MASSACHUSETTS.

DIAL-POSITIONING AND YARN-FEEDING MECHANISM FOR DIAL KNITTING MACHINES.

Application filed June 30, 1920. Serial No. 392,917.

- This invention relates to improvements in knitting machines of the type having means for making stockings or other articles of hosiery with properly coordinated exchanges of the knitting yarns, or the inclusion of additional or auxiliary yarns, or both, and specifically to an improved machine of this type also adapted to make integral inturned welts.
- 5 In my Letters Patent Nos. 1,256,062, dated February 12, 1918, and 1,282,958, dated October 29, 1918, I have explained a satisfactory mechanism for taking and holding bights of yarn internally of the knitting needles for the purpose of making a welt, of such a nature as to permit the proper clamping and severing of withdrawn yarns, such as exchanged yarns, or a splicing yarn, above the dial or holder for the transfer bits 10 or implements employed to hold the bights for welting purposes and above the cap or cam carrier for working these instruments, and also adapted to permit the passage of runs or floats of certain yarns beneath the 15 dial.
- Additional or auxiliary yarns employed for splicing, or for making thickened-wale structures like those of my Letters Patent Nos. 1,256,834, dated February 19, 1918, 20 1,267,126, dated May 21, 1918, and 1,267,127, dated May 21, 1918, are also floated beneath the instrument dial during the operation of including them in the fabric, and withdrawn, 25 severed and clamped above the dial-cap carrying the operating cams when their function is completed. The withdrawn yarn for the ordinary yarn changes is severed and clamped ready for reentry above the dial cap.
- When knitting fabric for a welt, it is expedient to dispose this fabric within and beneath the dial by the operation of a presser instrument bearing on the fabric between the loops or bights held by the transfer bits or 40 instruments and the course being knit by the needles, for instance as shown in my said Patents Nos. 1,282,958, and 1,256,062. When the instruments in the dial take and withhold bights or loops, it is desirable that their 45 vertical position should be as near the knocking-over line or position of the forming knit course as possible.
- For the purpose of floating yarns beneath the dial or the operation of a welt-presser on 50 the one hand, and for the taking of bights or
- loops and the severing and clamping of yarns above the dial on the other hand, the desirable positions of the dial and its adjuncts are different and inconsistent.
- Principal objects of this invention are to 60 provide for lowering the yarn-receiving and delivering platform in respect to the needles during each yarn change or insertion of new yarn; to provide means for positioning the transfer-bits or welting instruments at a low 65 point near the knocking over level for the knit courses during their bight-taking operation, and thereby to provide for making a transfer-course with shorter and less noticeable loops; to provide for increasing the 70 clearance under the dial and transfer-bits during the operation of the welt presser; to provide for increasing the gap between the verges of the needle-cylinder and dial for the purpose of providing room for the introduction of a thick or heavy yarn while making a thickened-wale structure or mock-seam; and to provide simple and efficient automatic 75 means capable of easy attachment to and cooperation with the other mechanism. A 80 further object is to provide a mechanism for these purposes for raising and lowering a dial coordinately with the motions of yarn guides cooperating with the needles to enter and remove yarns, and coordinately with 85 means for severing and clamping the withdrawn yarn.
- In the accompanying drawings showing preferred mechanism, as specific instances only;
- Fig. 1 is a central vertical section through the needle cylinder of a machine corresponding to my Patent No. 1,282,958, illustrating one form of the invention;
- Fig. 2 is an explanatory enlarged detail 90 showing transfer bits or welting instruments, a web-holder and needles;
- Fig. 3 is a section on line 3—3 of Fig. 5, some of the parts being removed, showing one type of mechanism for positioning the 95 dial and its adjuncts;
- Fig. 4 is a plan illustrating the parts shown in Fig. 3;
- Fig. 5 is a section partly in elevation taken from the right-hand side of the device shown 100 in Fig. 3; and
- Fig. 6 is a view similar to Fig. 3 showing a modification.
- As in the patented machine, of which parts are shown in Fig. 1, the needle cylinder 105

260. the web holder bed 200 for the web-holders w , and the transfer or welting-instrument dial 4 are arranged to rotate in unison, preferred devices for this purpose including, 5 as best shown in Fig. 5, a vertical shaft 33 on the frame of the machine driven from the main shaft (not shown) which in turn drives the needle cylinder 260. Shaft 33 is provided with a pinion g^4 , meshing with a gear 10 g^8 , for rotating the horizontal countershaft 2, in turn provided with a pinion g^2 driving a bevel gear g' , now splined at g^5 to the vertical stem 3 of the dial 4. The ratio of the 15 gears driving the shaft 33 and of the gearing g^8 , g^4 and g^2 , g^1 , is such as to turn the dial 4 in unison with the motions of the cylinder 260.

As in the patented machine, the bearing for the stem 3 may comprise a bracket 1 20 having a bored vertical bearing sleeve 8 faced at the top to support the hub of gear g' and having a lower reduced portion upon which the bored central boss 6 of a dial cap 5 finds an exterior bearing for vertical 25 movement. Rotary movement of the cap 5 is restrained by appropriate means, such as the vertical stud 10 passing through a hole 11 in bracket 1 and attached at the bottom to cap 5 and at the top to an arm 30 of a plate 13 having a bearing hole for the spindle 3, upon which it is retained by a cap 14 and screw 15 fast on and rotating with the spindle 3. Plate 13 provides or carries a limit stop fixing the downward limit 35 of motion of the spindle 3, stud 10, dial 4 and cap 5 otherwise permitted by the spline g^5 ; preferably this stop is an adjusting screw 16 in a hole in plate 13, having a lock-nut 17, and having a point projecting beneath the plate to bear on supporting means adapted to carry the weight of the parts.

The vertical position of dial 4, spindle 3, cap 5 and stud 10 is automatically adjustable, preferably by movement of the 40 supporting means; as shown in Figs. 3, 4 and 5, the supporting means comprises a sliding cam bar 21 extending transversely of the spindle 3 and movable in a slot 20, Fig. 5, provided for it in the gear-casing K 45 fixed on the bracket 1. The upper surface of slide bar 21 is formed into steps for screw 16, as shown a high step a , an intermediate step b , and a longer low step c , connected by cam inclines. Motion of slide 50 bar 21 will thus result in lifting or lowering the dial and its adjuncts to different levels, adjustable by turning screw 16, and in holding these parts fixed by gravity at the level determined by the lateral position 55 at which the slide bar 21 is left. As shown, the dial 4 may be so moved from one to another or left in any of the positions for a given point represented by the levels I, II and III, Fig. 3, corresponding respectively 60 to the steps a , b , and c .

I have devised means for raising and lowering the dial and leaving it at the desired level by the pattern-controlled connections which are employed to work the 70 yarn severing and clamping means, thus once avoiding an additional pattern-operated connection and securing proper coordination between the yarn-feeding, severing and clamping means and the means for positioning the dial and its adjuncts. 75

The severing and clamping means shown comprises a guide clamp 7 for the withdrawn idle yarn made as a lever resting on the upper surface of the dial cap 5 and adapted to be positively opened to receive 80 yarn by motion about its pivot 9 in an ear of the boss 6, whenever the movable blade 25 of the severing device is opened by turning the blade 25 about its pivot 26 on boss 6. The clamp and the blade are opened by 85 moving to its lowermost position a wire link 27 connected at one end to blade 25 and at the other end to a shackle 28 pivoted at 29 on the inner end of arm 611^b of an actuator lever 611 pivoted at 612 on the latch-ring 90 550. Lever 611, as heretofore, is moved by one of the series of thrust-bars 460 worked by cams 121 or 122 on the pattern-drum 120 which determines the times of yarn-feeding 95 and other motions of parts of the machine. Motion of lever 611 takes place to depress link 27 and open the clamp and severing blade whenever it is necessary to receive a 100 yarn withdrawn by lifting one of the yarn fingers F (to carry the withdrawn yarn above the cap 5 and into the opened clamp and severing means) as explained fully in my said Patents Nos. 1,282,958 and 1,256,062. Arm 611^b of lever 611 is pressed upward by a plunger 34 and strong spring 105 31 in a bore 32 in bracket 1.

In order to improve the yarn-feeding and withdrawing function of the parts, I provide that motion of the dial cap and dial 110 downwardly to a low position shall occur preparatory to every exchange, entry or withdrawal of yarn. This position enables the various yarn feed instruments to deliver their yarns upon the yarn-holding and delivering platform defined by the upper 115 surface of dial cap 5 by a shorter motion upward of the yarn-guide or finger; this position also causes the yarn, when it is so withdrawn, after rotation of the fabric in respect to the dial cap to pass above this 120 platform through a lesser angle or at an earlier time than heretofore; and this position further enables a yarn to re-enter upon the needles while the held end is at a low point in relation to the needles and web-holders. The accuracy of leaving and of 125 reentry of yarns at the needles is thus increased by positioning the yarn at a more favorable angle, and by causing deeper entry between the needles by a shorter and 130

quicker downstroke, and withdrawal by a shorter and quicker upstroke of the movable yarn finger, than could be the case if the yarn were received and clamped, or delivered, from a higher level.

Slide 21 may be connected in any convenient way to lever 611; as shown, a shoudered pivot screw 35 is adjustably locked in a sector slot 36 of an upward extension 611^a 10 of lever 611, and takes into a hole in one end of slide 21.

In the preferred forms shown by way of illustration, spring 31 is capable of moving the lever 611 and slide 21 strongly enough 15 to lift the dial and dial-cap and other parts carried by the spindle 3 by the motion of the cams on slide 21 under the screw stop 16. Normally, screw 16 rests on the high part *a* of the slide 21, and the dial and its adjuncts 20 are lifted to position I, Figs. 1 and 3. The dial may be lowered to position II prior to opening of the severing blade 25 and clamp 7 by lifting the thrust bar 460 through a lesser distance than that required 25 fully to depress link 27, by providing cams 122 on drum 120 each having a preliminary step *d* high enough to move the step *b* of slide 21 under screw 16. The dial may be lowered to the lowest position III preliminary 30 to opening the blade 25 and clamp 7 by providing a cam 121 with a preliminary step *e* higher than step *d* of cam 122, and capable of moving slide 21 to bring its step *c* under screw 16. At the cam 121, the dial 35 retains its lowest position III until further motion of drum 120 brings the high part of cam 121 under the thrust-bar 160 and the operation of either cam 121 or cam 122 results in first opening blade 25 and clamp 7, 40 and in thereafter, as bar 460 runs off the cam, closing these parts to sever and clamp a yarn introduced while the dial is in one of its lower positions, and in then lifting the dial to its normal high position. The cams 45 122 need not be different from cams for working the severing and clamping means employed in the machine of my Patent No. 1,282,958, and may as heretofore, be placed on drum 120 in alignment with other cams 50 on the drum for moving other thrust-bars 460 to work a pair of the yarn-fingers F to enter one whose yarn has been idle and clamped under clamp 7, and then to withdraw another finger F.

55 As explained in my said Patents Nos. 1,256,834, 1,267,126 and 1,267,127, an additional or auxiliary yarn for making thickened wale structures may also at times in the operation be fed from another position 60 than the delivery position of the yarn-fingers F, and this additional auxiliary yarn may also be received when withdrawn beneath the guiding clamp 7 and severed by the blade 25. The auxiliary yarn may for 65 instance be fed from a yarn-eye in a varn

guide *t'* delivering its yarn at the opposite side of the needle cylinder 260 from the yarn fingers F.

The motion of the dial for this purpose may if desired be confined to lowering the dial when the yarn *t* is withdrawn and severed by a properly placed cam 122.

It will be observed that the motions of the dial and cap mentioned are all made without changing the normal relation to each other of these parts, and that when the parts are in the intermediate position II or lower the yarn platform on the top of cap 5 is favorably positioned for entering a new yarn, or for a yarn-change. This position is 80 reached without having opened the clamp 7 to free the yarns; opening the clamp 7 and blade 25 does not occur until slide 21 has moved to the right, Fig. 3, to bring screw 16 on the step *c*, when the parts are in their 85 lowest position III. The step *c* on slide bar 21 being elongated, as mentioned above, bar 21 can slide under screw 16 without altering the position of the dial and cap. The parts now remain in the lowest position III, 90 screw 16 remaining on step *c* until the reverse movement of slide bar 21 occasioned by thrust-bar 460 running off the cam 121 or 122 has been in part completed during motion of step *c* past screw 16; during this 95 time the withdrawing finger F will have lifted its yarn, the relative motion of the fabric will have carried the withdrawn yarn under clamp lever 7 and blade 25, and these parts will have been actuated to clamp and 100 sever the yarn before the completion of movement to the left of slide bar 21 returns the parts to position I.

A low position for the dial 4 and cap 5 is particularly desirable when the transfer bits T are to be positioned as shown in Fig. 2 to receive bights of yarn between some of the needles. It is advisable on this occasion to position the yarn receiving parts T' of the bits T as near the knocking over line defined by the upper arm of web-holders w as possible, so that the least draught possible 110 upon the yarn follows feeding it to both the needles and the hooked ends T' of the transfer bits T.

With the above-described devices, this is effected by placing a cam 121 on drum 120 at the place represented by the time for the advance outwardly of the bits T to take bights. The step *e* of this cam 121 moves 115 the dial and its adjuncts downwardly to the lowest position III in time with or previous to the adjustment of a cam A of my said patented machine on cap 5 for moving out the bits T, and retains the parts in this position during at least one course. If a different yarn is employed for this course, the cam 121 also serves to work the severing and clamping means for this yarn; if this 120 yarn is a yarn to be knit for following fab. 125

ric, for instance to make the fabric for a welt, it will not be withdrawn, and actuation of the clamp and severing means by the highest part of cam 121 will occur idly, no 5 yarn having been thrown into the clamp and severing means to be clamped or severed.

The dial 4 can be lowered to position III during actuation of the bits T for the above 10 and other purposes without interfering with the web-holders w, since the wave of projection of the bits T by cam A occurs at the place of a wave of withdrawal of the web-holders for their normal action resulting 15 from the effect of normally positioned web-holder withdrawing cams forming a part of my said patented machine.

Referring now to Fig. 1, when the bights of yarn have been hung upon the transfer 20 bits T to make an inturned welt, it has always been customary to introduce a thin blade P, under the stress of a light spring, between the cylinder and dial; this blade presses the fabric inward away from the 25 needles until after the welt knitting is well started. Room to pass this blade under the dial has heretofore been provided by fixing the dial at a higher point than otherwise necessary.

30 It will be observed that the normal position I of the dial according to the present invention is amply high enough to admit the blade P and the welt fabric under the dial. The blade P may be introduced at any time 35 after the passage of cam 121 past thrust-bars 460, and may be withdrawn by suitably moving its operating thrust-bar 463 to permit lowering the dial for a yarn change at any time thereafter, and may be again introduced if desired.

When the yarn-guide t' is operated to introduce its yarn t for a thickened-wale structure, the normal high position of the dial clears a free space between the verge of 45 the cylinder and the upper edges of the web-holders amply wide to permit the yarn t, which is usually a heavy and thick yarn, to sweep unobstructedly in this space and beneath the dial.

50 When one of the fingers F is operated for splicing, the normal high position of the dial is similarly of advantage in removing the verge and lower face of the dial upwardly beyond reach of the floating run of 55 the splicing yarn thrown across the width of the cylinder at each course.

While the described constructions are preferred, it will be plain that similar advantages may be secured by modified forms. 60 Fig. 6 illustrates one of these, in which the lever 611, otherwise constructed and operating as above described, is provided with an integral cam arm 611^b replacing the slide bar 21, and having for this purpose steps 65 a', b', c', concentric with the pivot 612 and

joined by cam inclines, to take under and support directly the screw 16 in a suitable extension of the plate 13, and thereby to control the vertical position of the dial, the dial-cap and their adjuncts. In this form, 70 the point of application of the dial lifting and supporting means may be duplicated by providing an adjustable collar 40 on stud 10 to take over a pin 41 on arm 611^b of lever 611, the steps a', b', c' being separated 75 by radial distances from the center 612 conforming to the vertical displacement of pin 41 when the lever 611 is swung on the pivot 612 through the angular distances between the respective steps a', b', c'. Motion in response to spring 31 is thus applied at both 80 41 and 16.

In either form of the device, an adjustable collar 42 on stud 10, Fig. 6, may be applied to limit the lowest position of the dial 85 and its adjuncts by contact with bracket 1.

It will now be readily understood that the invention is independent of the particular machine in connection with which I have elected to describe it.

90 The dial 4 and dial-cap 5, for instance, may well be, instead of the illustrated parts, the corresponding parts of any type of machine for knitting ribbed fabric, or partly ribbed and partly plain fabric, and having 95 for these purposes knitting needles in the dial and their appropriate adjuncts, instead of or in addition to the transfer implements T shown. Cooperation of the means for raising and lowering the dial and the means 100 for feeding and withdrawing yarn in such machines is important in the same way as in the illustrated species; and in such machines, the devices herein described for raising and lowering the dial are applicable and 105 independently useful when knitting tubular 110 welts, making loose courses or shogged work, changing the gauge of the fabric and for other purposes, whether or not these uses are associated with changes of yarn.

I claim:

1. A knitting machine having needles, a dial and means adapted to be positioned to feed yarn to the needles and moved to withdraw the yarn from feeding contact with the needles, in combination with means for automatically raising and lowering the dial in relation to the operative position of the yarn feeding means, and means for operating the means for feeding yarn during the operation 115 of the machine.

2. A knitting machine having therein needles and a yarn-feed guide movable respectively to feed yarn to and to withdraw the yarn from the needles, holding means for withdrawn yarn, and means for lowering the position of the yarn holding means coordinately with the operation of the yarn feed 125 guide.

3. A knitting machine having therein a 130

- circle of needles and means for feeding yarn to and withdrawing yarn from the needles, yarn holding means for withdrawn yarn within the needles, and means for altering 5 the level of the yarn holding means in respect to the needles and the yarn feeding means coordinately with operation of said yarn feeding means.
4. A knitting machine having therein 10 needles, a dial, means above the dial for receiving a withdrawn yarn, means for entering yarn upon and withdrawing yarn from the needles, and means for shifting the position of the dial and said receiving means to 15 alter the relation of the receiving means to the yarn at the time of withdrawal.
5. A knitting machine having therein 20 needles, a dial, and a cap therefor, means above the dial cap for receiving a withdrawn yarn, means for entering yarn upon and withdrawing yarn from the needles, and means for shifting the position of the dial cap and said receiving means to alter the 25 relation of the receiving means to the yarn at the time of withdrawal.
6. A knitting machine having therein 30 needles, a dial, means above the dial for receiving and holding a withdrawn yarn, means for entering yarn upon and with- 35 drawing yarn from the needles, and means for vertically shifting the position of said receiving and holding means to alter the relation of the receiving and holding means to the yarn at the time of entry into the receiving and holding means.
7. A knitting machine having therein 40 needles, movable yarn feeding means, and means for holding a withdrawn yarn behind the needles in combination with means for moving the yarn holding means to one position to receive a withdrawn yarn, and to another position to permit freedom of motion for a yarn floated behind the needles at 45 times in the operation.
8. A knitting machine having therein 50 needles, a dial, movable yarn feeding means, and means for holding a withdrawn yarn behind the needles and above the dial in combination with means for moving the dial and the yarn holding means to one position to receive a withdrawn yarn, and to another position to permit freedom of motion for a yarn floated behind the needles and under the dial at times in the operation.
9. A dial knitting machine having therein, in combination, means for manipulating 55 yarns, automatic means for operating the yarn manipulating means at predetermined times, and automatic means for raising and lowering the dial co-ordinately with the operation of the yarn manipulating means.
10. A dial knitting machine having therein 60 means for severing and clamping yarn at a point above the dial, yarn feeding means actuated at predetermined times, and means 65 for actuating the severing and clamping means coordinately with the yarn feeding means, in combination with means cooperating with said mechanism to alter the level of the dial to aid the operation of the yarn feeding means in respect to delivery of the yarn to the severing and clamping means and the needles respectively.
11. A dial knitting machine having therein 70 means for severing and clamping a withdrawn yarn at a point above the dial, and means for feeding a thickening-wale yarn adapted to be severed and clamped by said means when withdrawn, in combination with means for normally holding the dial in an elevated position to afford clearance beneath it for said yarn, and means for lowering the dial coordinately with withdrawal of said 75 yarn for severing and clamping.
12. A dial knitting machine having therein 80 means for severing and clamping a withdrawn yarn at a point above the dial, pattern controlled means adapted to open and close the clamping means, and means operated by said pattern-controlled means for changing the level of the dial preparatory to 85 actuation of said clamping means.
13. A dial knitting machine having therein 90 needles and means for severing and clamping a withdrawn yarn above the dial, 95 yarn feeding means adapted to deliver yarns to the needles, to float certain yarns behind some of the needles, and to withdraw yarns for entry into said severing and clamping means, in combination with means for automatically actuating said yarn feeding 100 clamping and severing means for said purposes, and means cooperating with said automatic actuating means to raise and to lower the dial respectively during the yarn-floating and the yarn-severing and clamping operations.
14. A dial knitting machine having therein 105 means for severing and clamping a withdrawn yarn, a movable connection for operating said severing and clamping means, means for supporting the dial, and means having a part movable by said connection for altering the position of said supporting means.
15. A dial knitting machine having therein 110 means for severing and clamping a withdrawn yarn, a movable operating connection, means for supporting the dial, and means having a part movable by said connection for altering the position of said supporting means during one part of the motion of said connection, the severing and clamping means being operable by said connection during another part of said motion.
16. A knitting machine having therein a latch-guard structure and a dial and dial cap supported on the latch-guard structure, means for rotating the dial and pattern controlled means having a movable element 115 120 125 130

bearing on an attachment of the latch-guard structure for altering the plane of rotation of the dial and the position of the dial cam in respect to the latch-guard structure during operation.

17. In a knitting machine having a rotary dial and driving connections therefor, a driving and supporting spindle for the dial movable in respect to the driving means therefor, an actuator lever, and means worked thereby for variably limiting the position of the spindle and dial against downward stress thereon.

18. In a knitting machine having a rotary dial and driving connections therefor, carried by a latch-guard structure, a driving and supporting spindle for the dial movable in respect to the driving means therefor, an actuator lever pivoted on the latch-guard structure, and means worked thereby for variably limiting the position of the spindle and dial against downward stress thereon.

19. In a knitting machine, a needle cylinder, a dial and supporting and driving means for the dial comprising a vertical dial spindle free to move axially in respect to its driving means, a plate bearing on the spindle confined against axial movement thereon, a stop on the plate, a cam bearing on a relatively fixed part having steps for the stop, and means for adjusting the cam to determine different levels for the dial.

20. A knitting machine having therein a needle cylinder and needles and means for making fabrics thereon having welts comprising a dial, instruments in the dial for taking and holding bights, and means for

actuating the instruments, a presser adapted to be entered between the cylinder and dial 40 at the time of making a welt, and means for moving the dial to a low position for taking bights and to a higher position for entry of the presser.

21. A knitting machine having therein a 45 needle-cylinder and needles, web-holders and means for retracting the web-holders in a wave, and means for making fabrics thereon having welts comprising a dial, instruments in the dial for taking and holding 50 bights, and means for projecting these instruments to take bights in a wave coincident with the wave of retraction of the web-holders, in combination with means for lowering the dial and instruments to a plane 55 coincident with parts of the web-holders during the bight-taking operation, and for subsequently raising the dial.

22. A knitting machine having therein needles, a dial and means adapted to raise 60 and lower the dial in stages corresponding to desirable positions of the dial and adjuncts carried thereby in relation to the motions of yarns fed to the needles and withdrawn therefrom, in combination with a 65 main pattern surface, yarn feeding means, and connections from the pattern surface for moving to and holding the dial in an appropriate stage of its positions in consonance with the automatic actuation of the 70 yarn feeding means controlled by said pattern surface.

Signed by me at New York, N. Y., this 29th day of June, 1920.

ROBERT W. SCOTT.
